UNITED STATES PATENT OFFICE

WALTER VAN E. THOMPSON, OF LOS ANGELES, CALIFORNIA, ASSIGNOR TO THOMPSON MANUFACTURING COMPANY, OF LOS ANGELES, CALIFORNIA, A CORPORATION OF CALIFORNIA

SPRINKLER HEAD HAVING A REMOVABLE NOZZLE UNIT

Application filed June 25, 1928. Serial No. 287,919.

My invention relates to irrigation sprinklers, and relates particularly to the type of sprinkling systems having a detachable sprinkler-unit which is above the ground level, and an underground portion having a permanent part to which the detachable sprinkler-unit may be attached. This type of irrigation system is used on playgrounds, golf courses, and the like, because during the use of the property there are no projecting parts of the sprinkler system which will interfere with the use of the property. When it is desired to irrigate the property, the detachable sprinkler-unit may be attached to the permanent part of the underground portion.

This type of sprinkler is usually made so that the sprinkler-unit opens a valve in the underground portion, when it is attached thereto. In the ordinary form of sprinkler system of this nature, the sprinkler-unit is attached to the underground portion by a latch-means. The valve-opening means is so constructed that the valve is opened before the sprinkler-unit is entirely placed on the underground portion. This allows the water to leak, and it will spray onto the operator. A further disadvantage is that the area around the permanent portion is usually muddy because of the excess of irrigation.

It is one of the objects of my invention to provide a sprinkler system of this character in which the sprinkler-unit is connected to the permanent part before the valve is opened. This feature is advantageous inasmuch as it prevents leakage during the installing of the sprinkler-unit.

It is also an object of this invention to provide a sprinkler system in which the valve of the permanent part is closed before the sprinkler-unit is detached from the permanent part. This feature prevents a leakage during the removal of the sprinkler-unit.

A still further object of my invention is to provide a sprinkler system in which the sprinkler-unit is screw-threadedly connected to the permanent part of the system. This feature provides a reliable connection between these parts so that a fluid-tight connection is assured, and so that there is no

danger of the sprinkler-unit being inadvertently detached.

A still further object of the invention is to provide a sprinkler system of the character in which the permanent part has a water passage which is closed by a closure member, and in which the sprinkler-unit has a coupling portion which removes the closure from the end of the passage when the sprinkler-unit is installed. The coupling portion moves into the end of the passage as the closure is removed from the end of the passage. This feature of the invention prevents foreign matter from entering the permanent part, and furthermore provides for a tight closing for the permanent part when the sprinkler-unit is not installed thereon.

A further object of the invention is to provide a sprinkler system of the character referred to, in which the closure operates a valve of the permanent part, which valve closes the passage therethrough.

A further object of the invention is to provide a sprinkler system in which the closure is threadedly located in the end of the passage, and in which the sprinkler unit has means for rotating the closure to advance it from the end of the passage, the coupling portion of the sprinkler-unit also being threaded and being advanced into the threaded end as the closure is advanced from the threaded end.

It is another object of the invention to provide a sprinkler system of the character specified, in which the valve of the permanent portion is adjustable relative to the closure, so that it may be opened different degrees when the sprinkler-unit is attached in order to permit different volumes of water to pass through the sprinkler-unit.

It is a still further object of the invention to provide a sprinkler unit of the character specified, in which the closure carries means for positively seating the valve when the closure is in a closing position in the end of the passage. This feature of the invention positively prevents a leakage of water from the permanent part when the sprinkler-unit is not installed thereon.

A still further object of the invention is to

provide a sprinkling system of the character mentioned, in which the means for determining the amount that the valve is opened when the sprinkler-unit is installed in place, 5 may be adjusted while the sprinkler-unit is detached, and may be adjusted from the top of the permanent part without disassembling any of the parts.

It is a still further object of the invention 10 to provide a sprinkler system in which the closure is engaged by the sprinkler-unit, and moved from the end of the opening, and in which a coupling part of the sprinkler-unit simultaneously moves into the opening. After 15 the coupling part of the sprinkler-unit is at least partly in the end of the passage, the closure engages and opens the valve so that a flow of water occurs.

It is another object of the invention to provide 20 a sprinkler system in which the closure is moved into the end of the passage, when the coupling part of the sprinkler-unit is moved therefrom, and in which the closure, when it is in closing position in the opening, 25 engages the valve and positively clamps it against its seat.

I have briefly enumerated what I consider 30 to be the most important objects of the invention. In the following description, other objects of the invention will be described, and the construction of the invention which embodies these objects will be pointed out in detail.

In order that the invention may be readily 35 understood by those skilled in the art, I shall refer during the following description to the accompanying drawings, in which

Fig. 1 is an elevational view partly in section showing that part of a sprinkler system 40 embodying the essentials of my invention. In this view the sprinkler-unit is shown in a position ready to be attached to the permanent part.

Fig. 2 is a sectional view showing the 45 sprinkler-unit in the process of being attached to the permanent part. This view illustrates the parts in such a position that the valve of the invention is about to be opened.

Figs. 3, 4, and 5 are sectional views taken 50 on the corresponding lines of Fig. 2.

Fig. 6 is an elevational section showing the 55 sprinkler-unit fully attached to the permanent part.

Fig. 7 is a section taken on the line 7—7 of 60 Fig. 6.

I will now describe in detail the parts shown in the drawings, which constitute my 65 invention.

The sprinkler system includes underground header-piping 11 provided with T's 12 from which vertical supply-pipes 13 extend. To the upper ends of the vertical supply-pipes 13, permanent parts 14 which em-

body the features of the invention, are secured.

I shall now describe in detail the construction of the permanent part 14, and the sprinkler-unit 15 which cooperates therewith. Threadedly secured at 20 at the upper end of the supply-pipe 13, is a shell 21, the upper end 22 of which is located at or slightly below the level 23 of the ground.

The shell 21 provides a water-passage 25. The upper end of the water-passage 25 is reduced in diameter, and is provided with a threaded-end 26. The upper part of the water-passage 25 is provided with three equi-spaced vertical guide-ribs 27, the upper ends of which have continuations 27a of the threads in the threaded-end 26. The central part of the shell 21 has an annular partition 28 which extends inwardly into the passage 25, and defines a cylindrical opening 29. The partition 28 constitutes a valve seat which is engaged by a valve 31, which will now be described.

This valve 31 includes a member 32 provided with an annular channel which receives a gasket 33, this gasket 33 being adapted to engage the partition 28 for forming a fluid-tight seal. Projecting upward inside the gasket 33 is a cylindrical wall 35 adapted to project through the cylindrical opening 29. The cylindrical wall 35 is provided with V-shaped notches 36 which act as a regulating means for the valve.

The lower portion of the part 32 is in the form of a cylindrical boss 36a, and is guided by guide-ribs 37 formed in the lower part of the passage 25. Threadedly secured in this cylindrical boss 36 is a cup-shaped member 38 providing a chamber 39 which is not in communication with the passage 25 below the partition 28.

The threaded end 26 of the shell 21 is adapted to be closed by a plug 42 which constitutes the closure of the invention. This closure 42 has a threaded opening 43, into which the upper end of a tube 44 is screwed. The lower end of the tube 44 extends through an opening 45 of the member 32 and into the upper part of the chamber 39. The lower end of this tube 44 is threaded, and a shoulder in the form of a nut 46 is screwed thereon. The nut 46 is adapted to engage a lower face 47 provided by the member 32 in the upper part of the chamber 39. The shoulder 46 is adapted to pull the valve 31 upwardly so that the gasket 33 positively and tightly engages its seat. The tube 44 and the shoulder 46 constitute the valve-closing means of the invention.

The central part of the tube 44 is reduced in size, as indicated at 49, and is provided with internal threads. Threadedly supported in this portion 49 of the tube 44 is a plunger 50. The lower end of the plunger 50 extends into the chamber 39, and is adapted to engage

the lower wall of the cup 38 for removing the valve 31 from its seat.

The upper end of the plunger 50 is provided with a diametral slot 51, so that the plunger 50 may be rotated and thus adjusted in position relative to the tube 44. It will be seen that the upper end of the plunger 50 is accessible from the top of the permanent part 14. The plunger 50 constitutes the valve-opening means of the invention.

The sprinkler-unit 15 has a coupling-part 60 to which a vertical column-pipe 61 is threadedly secured. The upper end of the column-pipe 61 is provided with a rotating sprinkler-head 62, which may be of any standard form. The coupling-part 60 is provided with handles 63 whereby it may be rotated. Projecting downward from the main portion of the coupling-part 60 is a threaded-portion 64 provided with external threads 65 of the same diameter and pitch as the internal threads in the end 26 of the shell 21. Supported in the lower part of a passage 66 formed through the coupling-part 60 is a diametral key 67, which projects downward on the lower part of the threaded-portion 64. This key 67 is adapted to extend into a key-slot 68 provided in the upper part of the closure 42, as is illustrated in the drawings. Threadedly secured at 70 to the coupling-part 60 is a guide-sleeve 71. The guide-sleeve 71 is cylindrical and is of such a diameter that it will receive the upper part of the shell 21. The guide-sleeve 71 is adapted to hold the coupling-part 60 in alignment with the shell 21 so that the threaded-portion 65 will be in alignment with the threaded-end 26 of the passage 25.

At the upper part of the threaded-portion 64, inside the guide-sleeve 71, is an annular packing-member 72 adapted to form a seal between the coupling-part 60 and the upper end 26 of the shell 21, when the sprinkler-unit 15 is connected to the permanent-part 14, as illustrated in Fig. 6.

In Fig. 1 of the drawings, the parts of the permanent-part 14 are shown in the position they occupy when the sprinkler-unit 15 is disconnected therefrom. It will be seen that the valve 21 is tightly closed, and that the closure 42 closes the upper end of the passage 25. All of the parts are at this time below the ground level 23, and will not interfere with any activities on the property. When it is desired to irrigate the property, the sprinkler-unit 15 is attached to the permanent-part 14. The operation of attaching the parts will now be described.

The sprinkler-unit 15 is placed in such a position that the key 67 extends into the key-slot 68, and the lower part of the guide-sleeve 71 extends around the upper part of the shell 21. The sprinkler-unit is shown in this position in Fig. 1. The sprinkler-unit is then rotated by means of the handles 63 in such a

direction that the plug or closure 42 is screwed downward from the threaded end 26 of the shell 21. As the closure 42 advances downward, the sprinkler-unit 15 moves downward therewith, and the threaded-portion 64 will be screwed into the threaded end 26 of the passage 25. The key 67 is made of a proper size so that the threads 65 of the threaded-portion 64 will properly enter the threaded-end 26 of the passage 25.

In Fig. 2, the sprinkler-unit 15 is shown partly connected to the permanent-part 14. In this figure the lower end of the threaded-portion 64 has entered the threaded-end 26. The closure 42 in this view is shown partly advanced from the threaded-end 26. It will be noted that the closure is engaging the continuations 27a of the threads of the threaded-end 26. Fig. 2 also illustrates the plunger 50 in engagement with the lower wall of the cup 38. In this position the plunger 50 is about to remove the valve 31 from its seat, and to permit a flow of water through the sprinkler-unit 15. It will be noted that the valve is not opened until after the threaded-portion 64 of the coupling-part 60 has entered the threaded-end 26 of the passage 25.

The sprinkler-unit 15 is rotated until the parts occupy the positions shown in Fig. 6. In Fig. 6 the threaded-portion 64 has completely entered the threaded-end 26, and the annular gasket or sealing-means 72 is in sealing contact with the upper end 22 of the shell 21. There is absolutely no possibility of any leakage. The lower end of the plunger 50, by reason of its engagement with the lower wall of the cup 38, has moved the valve 31 from closed position, as illustrated in Figs. 1 and 2, into open position as illustrated in Fig. 6. At this time the water will flow through the passage 25, as indicated by arrows 75, and into the sprinkler-unit 15 as indicated by arrows 76. The water pressure on the cup 38 holds the cup against the lower end of the plunger 50, as shown in Figs. 2 and 6.

The sprinkler-unit 15 is detached from the permanent-part 14 by rotating it in the opposite direction from which it is rotated to install it. When this rotation occurs, the threaded-portion 64 of the coupling-part 60 moves upward from the threaded-end 26 of the passage 25. The continuations 27a advance the closure 42 upward until it has entered the threaded-end 26 of the passage 25. The pressure of the fluid against the cup 38 causes the cup 38 to follow the plunger 50 upward until the partition is engaged. As shown in Fig. 2, the valve comes against its seat shortly after the closure 42 has entered the threaded-opening 26. As rotation of the sprinkler-unit continues, the closure 42 and the parts connected thereto continue to move upward. There is at this time a relative movement between the shoulder 46 and

the valve 31, the shoulder 46 moving toward the face 47 provided by the member 32. When the closure member 42 arrives at closing position, as indicated in Fig. 1, the shoulder 46 has moved into engagement with the face 47, and has clamped the gasket 33 against the lower wall of the partition 28, thus forming a fluid-tight seal.

The construction we have just described embodies all of the features of the invention which were pointed out in the statement of invention of the application.

Briefly enumerated, the most important advantages of the invention are as follows:

15. During the attaching and detaching of the sprinkler-unit 15, there is absolutely no leakage between the parts, in view of the fact that the valve 31 is not opened until after the threaded-portion 64 has entered the threaded-end 26, and in view of the fact that the valve 31 is closed before the threaded-portion 64 is entirely advanced from the threaded-end 26.

20. Another advantage results from threaded-ly connecting the sprinkler-unit 15 to the permanent part 14. This threaded connection makes it possible to form a fluid-tight seal, and assures that the sprinkler-unit 15 will not become inadvertently detached from the permanent part 14.

25. Another advantage of the invention results from the providing of the closure 42 which fills the threaded end 26 when the sprinkler-unit 15 is detached from the permanent-part 14.

30. This provision absolutely prevents any dirt or other foreign matter from entering the permanent-part 14, and obviates the possibility of any foreign matter interfering with the operation of the parts.

35. A further feature of the invention results from the provision of the adjustable plunger 50, which determines the time during the attaching of the sprinkler-unit 15 at which the valve 31 will be removed from its seat, and determines the amount that the valve will be opened. By screwing the plunger 50 upward the valve will be opened a smaller amount than is shown in Fig. 6, and by screwing the plunger 50 downward the valve will be opened a greater amount than is shown in Fig. 6.

40. Another advantage of the invention is that the plunger 50 is adjustable when the sprinkler unit 15 is removed, without requiring the dismantling of any of the parts of the permanent-part 14. As shown in the drawings, the upper end of the plunger 50 is accessible through the top of the opening 43 formed in the closure 42.

45. There are numerous other inherent and obvious advantages of the invention, which I believe have been made manifest in the foregoing description.

50. I have described the invention as embodied

in a sprinkler system. The principal of the invention is not limited to this particular art, but may be embodied in construction of other arts where it is desired to have parts equivalent to the operative parts illustrated in this application. In view of the breadth of the invention, I desire to have the invention construed in the scope of the appended claims.

55. I claim as my invention:

1. In a device of the class described, the combination of: a shell forming a passage; a valve adapted to close said passage; a closure adapted to close one end of said passage; means detachably connected to said shell for removing said closure from closing position, said means moving into the end of said passage as said closure is removed therefrom; and valve-opening means for unseating said valve as said closure is removed from closing position.

60. 2. In a device of the class described, the combination of: a shell forming a passage; a valve adapted to close said passage; a closure adapted to close one end of said passage; means for removing said closure from closing position, said means moving into the end of said passage as said closure is removed therefrom; valve-opening means for unseating said valve when said closure is removed from closing position; and valve-closing means for positively holding said valve against its seat as said closure is in closing position.

65. 3. In a device of the class described, the combination of: a shell forming a passage; a valve adapted to close said passage; a closure adapted to close one end of said passage; means for removing said closure from closing position, said means moving into the end of said passage as said closure is removed therefrom; adjustable valve-opening means for unseating said valve when said closure is removed from closing position; and valve-closing means for positively holding said valve against its seat as said closure is moved into closing position.

70. 4. In a device of the class described, the combination of: a shell forming a passage, said passage having a screw-threaded end; a valve adapted to close said passage; a closure adapted to screw-thread into said screw-threaded end of said passage; means for rotating said closure so as to advance same from said screw-threaded end, said means being screwed into said screw-threaded end of said passage as said closure is removed therefrom; and valve-opening means for unseating said valve as said closure is removed from closing position.

75. 5. In a device of the class described, the combination of: a shell forming a passage; a valve adapted to close said passage, said passage having a screw-threaded end; a closure adapted to screw-thread into said screw-threaded end of said passage; means for ro-

- tating said closure so as to advance same from said screw-threaded end, said means being screwed into said screw-threaded end of said passage as said closure is removed therefrom; and adjustable valve opening means for unseating said valve as said closure is removed from closing position. 6. In a device of the class described, the combination of: a shell having a passage, 10 said passage having a screw-threaded end; a closure screwed into said screw-threaded end for closing same; means for rotating said closure in order to advance same from said screw-threaded end, said means having a screw-threaded portion which is advanced into said screw-threaded end when said closure is advanced from said screw-threaded end; a valve adapted to close said passage; and a valve-opening means operated by said 15 closure for opening said valve as said closure is advanced from said screw-threaded end. 7. In a device of the class described, the combination of: a shell having a passage, 20 said passage having a screw-threaded end; a closure screwed into said screw-threaded end for closing same; means for rotating said closure in order to advance same from said screw-threaded end, said means having a screw-threaded portion which is advanced into said screw-threaded end when said closure is advanced from said screw-threaded end; a valve adapted to close said passage; and a stem threadedly held by said closure, 25 adapted to engage said valve, for opening said valve as said closure is advanced from said screw-threaded end. 8. In a device of the class described, the combination of: a shell having a passage, 30 said passage having a screw-threaded end; a closure screwed into said screw-threaded end for closing same; means for rotating said closure in order to advance same from said screw-threaded end, said means having a screw-threaded portion which is advanced into said screw-threaded end when said closure is advanced from said screw-threaded end; a valve adapted to close said passage; and a stem threadedly held by said closure, 35 adapted to engage said valve, for opening said valve as said closure is advanced from said screw-threaded end. 9. In a device of the class described, the combination of: a shell having a passage, 40 said passage having a screw-threaded end; a closure screwed into said screw-threaded end for closing same; means for rotating said closure in order to advance same from said screw-threaded end, said means having a screw-threaded portion which is advanced into said screw-threaded end when said closure is advanced from said screw-threaded end; a valve adapted to close said passage; and a valve-opening means operated by said 45 closure for opening said valve when said closure is advanced from said screw-threaded end; a valve closing means for positively holding said valve against its seat as said closure is moved into closed position in said screw-threaded end. 10. In a device of the class described, the combination of: a shell having a passage, 50 said passage having a screw-threaded end; a closure screwed into said screw-threaded end for closing same; means for advancing said closure from said screw-threaded end, said means having a screw-threaded portion which is advanced into said screw-threaded end as said closure is advanced from said screw-threaded end; guide means for guiding said means into said screw-threaded end; a valve adapted to close said passage; and a valve-opening means operated by said closure for opening said valve simultaneously with the advancement of said closure from said screw-threaded end. 11. In a device of the class described, the combination of: a shell having a passage, 55 said passage having a screw-threaded end; a closure screwed into said screw-threaded end for closing same; means for advancing said closure from said screw-threaded end, said means having a screw-threaded portion which is advanced into said screw-threaded end as said closure is advanced from said screw-threaded end; guide means for guiding said means into said screw-threaded end; a valve adapted to close said passage; a valve-opening means operated by said closure for opening said valve as said closure is moved into closed position in said screw-threaded end. 12. In a device of the class described, the combination of: a shell having a passage, 60 said passage having a screw-threaded end; a closure screwed into said screw-threaded end for closing same; means for advancing said closure from said screw-threaded end, said means having a screw-threaded portion which is advanced into said screw-threaded end as said closure is advanced from said screw-threaded end; guide means for guiding said means into said screw-threaded end; a valve adapted to close said passage; and a valve-opening means operated by said closure for opening said valve simultaneously with the advancement of said closure from said screw-threaded end. 13. In a device of the class described, the combination of: a shell having a passage, 65 provided with a screw-threaded end; a closure screwed into said screw-threaded end

for closing same; means for rotating said closure to advance same from said screw-threaded end and having a screw-threaded portion adapted to be advanced into said screw-threaded end when said closure is advanced from said screw-threaded end; guides for guiding said means in the said screw-threaded ends; a valve adapted to close said passage; and valve-opening means operable by said closure for simultaneously opening said valve as said closure is advanced from said screw-threaded end.

14. In a device of the class described, the combination of: a shell having a passage provided with a screw-threaded end; a closure screwed into said screw-threaded end for closing same; means for rotating said closure to advance same from said screw-threaded end and having a screw-threaded portion adapted to be advanced into said screw-threaded end; guides for guiding said means into said screw-threaded end; a valve adapted to close said passage; valve-opening means operable by said closure for simultaneously opening said valve as said closure is advanced from said screw-threaded end; and valve-closing means for positively holding said valve against its seat as said closure is moved into closed position in said screw-threaded end.

15. In a device of the class described, the combination of: a shell having a passage provided with a screw-threaded end; a closure screwed into said screw-threaded end for closing same; means for rotating said closure to advance same from said screw-threaded end and having a screw-threaded portion adapted to be advanced into said screw-threaded end when said closure is advanced from said screw-threaded end; guides for guiding said means into said screw-threaded end; a valve adapted to close said passage; valve-opening means operable by said closure for simultaneously opening said valve as said closure is advanced from said screw-threaded end; and valve-closing means for positively holding said valve against its seat simultaneously with the movement of said closure into closed position in said screw-threaded end.

16. In a lawn sprinkling device of the class described, the combination of: a shell adapted to be attached to a supply system, said shell having a passage; a closure adapted to close said passage; a removable part having a conduit, said removable part adapted to be placed with said conduit in communication with said passage, said removable part being adapted to unseat said closure when said removable part is attached to said shell; a valve adapted to close said passage; and valve-opening means carried by said closure for unseating said valve, said valve-opening means being adjustable so that said valve may be unseated different amounts in order to per-

mit different amounts of fluid to flow through said passage.

17. In a device of the class described for use in sprinkling systems, the combination of: a shell having a passage; a closure member for closing said passage; a valve member adapted to seat in said passage; and an unseating means adjustably carried by one of said members whereby said valve member is unseated when said closure member is in non-closing positions, there being an opening in said closure member through which said unseating means is accessible.

In testimony whereof, I have hereunto set my hand at Los Angeles, California, this 19th day of June, 1928.

CERTIFICATE OF CORRECTION.

Patent No. 1,875,780.

September 6, 1932.

WALTER VAN E. THOMPSON.

It is hereby certified that error appears in the printed specification of the above numbered patent requiring correction as follows: Page 4, line 97, claim 2, for the word "in" read moved into; and that the said Letters Patent should be read with this correction therein that the same may conform to the record of the case in the Patent Office.

Signed and sealed this 22nd day of November, A. D. 1932.

(Seal)

M. J. Moore,
Acting Commissioner of Patents.
